Attorneys.

UNITED STATES PATENT OFFICE.

SYLVESTER DAVIDSON FAIRWEATHER, OF NEWBURGH, SCOTLAND.

FOOTWEAR.

1,331,844.

Specification of Letters Patent. Patented Feb. 24, 1920.

Application filed November 6, 1918. Serial No. 261,336.

To all whom it may concern:

Be it known that I, SYLVESTER DAVIDSON FAIRWEATHER, a subject of the King of the United Kingdom of Great Britain and Ireland, and residing at Newburgh, Aberdeenshire, Scotland, have invented a certain new and useful Improvement in Footwear, of which the following is a specification.

This invention relates to improvements in footwear and consists in the formation of a boot or shoe in such wise that the metatarso-phalangeal joint of the big toe, all the toes themselves, the outer part of the sole of the foot, and the heel, shall rest on one plane, parallel to the surface on which the sole of the boot or shoe rests; the heel and the forward portion of the sole of the boot or shoe being co-planar and the intermediate portion of the inner side part of the foot-supporting surface of the boot or shoe being arched or curved convexly upward in approximate conformity with the arch at the inner side of the foot.

In a boot or shoe so formed the heel portion and the sole portion which supports the ball of the foot are of practically the same thickness and may be comparatively rigid. The intermediate arched portion of the sole under the arch of the foot should possess a certain flexibility and fit like a glove under the arch of the foot.

There may be built into the arched portion of the sole a metallic spring arched both laterally and anteroposteriorly in correspondence with the arch of the foot, which spring may be formed with a flange at right angles thereto.

The sole and metallic spring may, if desired, be curved to fit the anterior transverse arch of the foot; such additional curvature is not necessary, however.

For the purpose of the present specification the term "sole" is employed to include any leather which underlies the arch of the foot; in practice the "upper" leather may be brought under the arch when great flexibility is desired, the actual sole leather being cut narrower accordingly.

In the accompanying drawings which illustrate the invention as embodied in a boot, Figure 1 is an elevation of the inner aspect of the left boot. Fig. 2 is a vertical section of the outer side of the same. Fig. 3 is a transverse section through the arched portion of the sole.

As shown in the drawings the heel portion 1 and the sole portion 2 on which rest the toes and the ball of the foot are co-planar and of practically the same thickness so 60 that the metatarso-phalangeal joint of the big toe, all the toes, the outer part of the sole of the foot and the heel shall rest in one plane parallel to the ground. 3 denotes the intermediate portion which is arched both 65 laterally and anteroposteriorly as aforesaid. 4 denotes the spring above referred to. The inner edge of the boot or shoe is preferably straight so that the big toe may be in line with the inner side of the arch. 70

Footwear such as described and shown may be of leather or of any other suitable material, with or without the incorporation of spring metal reinforcement.

What I claim is:—

1. A boot or shoe formed as described and having a foot supporting surface for the metatarso-phalangeal joint of the big toe, the toes themselves, the outer part of the sole of the foot, and the heel all in one plane 80 which is parallel to the tread or outer surface of the sole of the boot or shoe, the tread surfaces of the heel and the forward portion of the sole of the boot or shoe being co-planar, and the intermediate portion of the 85 inner side part of the shoe being arched or curved in approximate conformity with the arch at the inner side of the foot.

2. A boot or shoe formed as described and having a foot supporting surface for the 90 metatarso-phalangeal joint of the big toe, the toes themselves, the outer part of the sole of the foot and the heel all in one plane which is parallel to the tread or outer surface of the sole of the boot or shoe, the tread 95 surfaces of the heel and the forward portion of the sole of the boot or shoe being co-planar, and the intermediate portion of the inner side part of the shoe being arched or curved in approximate conformity with the 100 arch at the inner side of the foot, combined with an arched metallic spring curved to conform to the arched portion of the sole so as to reinforce the same.

In testimony whereof I have signed my 105 name to this specification in the presence of two subscribing witnesses.

SILVESTER DAVIDSON FAIRWEATHER.
